ASH TRAY

Seymour M. Gluck, 1320 Cornaga Ave.,
Far Rockaway, N.Y.

Filed Jan. 10, 1964, Ser. No. 78,158

Term of patent 14 years

(Cl. D85—2)

FIG. 2 is a top plan view thereof;

FIG. 3 is a sectional view taken on the line 3—3 of FIG. 2; and

FIG. 4 is an end elevational view looking in the direction of the arrows 4—4 of FIG. 2.

I claim:

The ornamental design for an ash tray, as shown.
